UNITED STATES PATENT OFFICE

HOMER LEROY PHELPS, OF MARTINSBURG, WEST VIRGINIA

CONDENSING DEVICE

Application filed August 2, 1927. Serial No. 210,065.

This invention aims to provide a novel means whereby liquids which are carried in suspension in the smoke proceeding from a wood fire, may be condensed and saved.

5 It is within the province of the disclosure to improve generally and to enhance the utility of devices of that type to which the invention appertains.

With the above and other objects in view 10 which will appear as the description proceeds, the invention resides in the combination and arrangement of parts and in the details of construction hereinafter described and claimed, it being understood that changes 15 in the precise embodiment of the invention herein disclosed, may be made within the scope of what is claimed, without departing from the spirit of the invention.

In the drawings:

20 Figure 1 shows in elevation, a device constructed in accordance with the invention, parts being in section;

Figure 2 is a top plan;

25 Figure 3 is a longitudinal section of the drum;

Figure 4 is a section taken about on the line 4—4 of Figure 1, remote parts being omitted;

Figure 5 is a section taken on the line 30 5—5 of Figure 3.

The numeral 1 marks a furnace, in which chips, saw dust, and wood of any kind may be burned. The numeral 2 designates an upright drum or tank, supported on legs 3.

35 A flue 4 communicates with the furnace 1, and includes a horizontal portion 5 which enters the upper portion of the drum 2, in tangential relation to the wall of the drum, as clearly shown in Figures 2 and 3 of the drawings. A pipe 6 extends downwardly through the top of the drum 2. Above the

40 drum 2, the pipe 6 has an enlarged portion 7. There is a damper 8 in the pipe 6, above the drum 2, the damper being under the control of an operator. A baffle disk 9 is secured to the lower end of the pipe 6 and is disposed close to the bottom of the drum 2. There is a space 10 between the periphery of the baffle disk 9 and the wall of the drum 2. A blast

45 pipe 11 communicates with the pipe 6 and

discharges into the horizontal portion 5 of the flue 4, lengthwise of the part 5, and into the top of the drum 2. In the blast pipe 11, a combined suction and blowing mechanism 12 is interposed, the mechanism 12 being 55 driven in any suitable way, for instance, by an electric motor 14, indicated diagrammatically in Figure 2. A drain pipe 15 communicates with the lower end of the drum 2 and discharges into any convenient receptacle 16, there being a valve 17 in the pipe 15. The pipe 15 is upwardly inclined to form a means for retaining a portion of the condensate, so that air cannot enter the tank by way of the pipe 15. The valve 17 also serves as a means for preventing air from finding its way into the tank through the pipe 15. A spray head 18 surrounds the pipe 6 and discharges downwardly on the drum 2, the spray head being connected to a pipe 70 19, wherein a hand valve 20 is interposed.

In practical operation, when wood or other material is burned in the furnace 1, the products of combustion pass upwardly through the flue 4—5 and enter the upper 75 end of the drum 2. Products of combustion having a whirling motion in the drum 2, owing to the way in which the part 5 of the flue discharges into the drum, and because a blast is delivered into the pipe 6, by way 80 of the pipe 11, the mechanism shown at 12 sucking the products of combustion out of the pipe 6 and blowing them into the pipe 11. Water flowing through the pipe 19 is distributed by the spray head 18 on the drum 2 and runs downwardly over the drum, thereby cooling the drum. Because the products of combustion enter the drum 2 with a whirling motion, and impelled by the blast through the pipe 11, the products 85 of combustion travel downwardly in the drum 2, in close contact with the cool wall of the drum, and a condensation is effected, the products of combustion being prompted to move close to the wall of the drum, because 90 the products of combustion must pass through the small space 10 which exists between the periphery of the baffle disk 9 and the wall of the drum 2. The liquid condensed out runs through the pipe 15 into 95 100

the receptacle 16, under the governance of the valve 17. The products of combustion rise through the pipe 6, under the control of the damper 8, and sometimes there is a slight condensation in the part 7 of the pipe 6, due to air cooling.

What is claimed is:—

1. In a device of the class described, an elongated cylindrical drum provided in its lower end with a liquid outlet, an annular spray head discharging downwardly on the top of the drum, means for supplying liquid to the spray head, an outlet pipe for the products of combustion, extended through the spray head and through the top of the drum to a point closely adjacent to the liquid outlet and the bottom of the drum, a baffle disposed close to the bottom of the drum, the baffle being disposed within the drum and on the lower end of the outlet pipe, the pipe having an enlarged portion disposed above the spray head, a damper in the pipe, below the said enlarged portion, an inlet pipe for the products of combustion, one end of the inlet pipe discharging into the side of the drum at a point near to the top of the drum, and in tangential relation to the drum, a third pipe one end of which is formed into a nozzle discharging into said end of the inlet pipe in tangential relation to the inner surface of the drum, the opposite end of said third pipe communicating with the outlet pipe at a point between the spray head and the damper, and means interposed in said third pipe for drawing gases from the outlet pipe and discharging the gases through the nozzle.
2. In a device of the class described, a tank provided near to its upper end with an inlet for the products of combustion, an outlet for condensate in the bottom of the tank, means for closing said outlet to prevent air from flowing into the tank by way of the outlet, an outlet pipe for gaseous products extended into the tank, and an imperforate baffle plate on the lower end of the outlet pipe, the area of the baffle plate being approximately the same as the cross section of the tank, thereby to bring the periphery of the baffle plate close to the side wall of the tank, and to cause the products of combustion to move downwardly from the inlet, in close relation to the wall of the tank, the baffle plate being located near enough to the bottom of the tank to hold the products of combustion close to a shallow body of condensate in the bottom of the tank, and mechanism for cooling the tank from end to end.
3. A device of the class described, constructed as set forth in claim 2, and further characterized by the fact that the mechanism for cooling the tank embodies a member disposed about the outlet pipe, externally of the tank, and discharging downwardly on the top of the tank to form a thin sheet

of cooling liquid around the tank from end to end, and means for supplying cooling liquid to the aforesaid discharging member.

In testimony that I claim the foregoing as my own, I have hereto affixed my signature.

HOMER LEROY PHELPS.
